VENTILATING RANGE HOOD

Samuel M. Bernstein, Winnetka, Ill.

Application March 14, 1956, Serial No. 40,613

Term of patent 7 years

(Cl. D81—25)

Fig. 1 is a perspective view of a ventilating range hood showing my new design;

Fig. 2 is a top plan view of the same; and

Fig. 3 is a side elevational view of the same.

The rear of the ventilating range hood not shown is substantially plain.

I claim:

The ornamental design for a ventilating range hood, substantially as shown and described.
